CATCH ASSEMBLY

Roy A. Stone and Leonard K. Ploughman, Rockford, Ill., assignors to National Lock Company, Rockford, Ill., a corporation of Delaware

Application August 12, 1954, Serial No. 449,382

1 Claim. (Cl. 292—70)

The present invention relates to a catch construction adapted for use in metal cabinets and the like for the retention of a swingably mounted or pivoted closure or door in closed position, and more particularly relates to a novel snap-in type of catch assembly adapted to be detachably mounted in an opening of a supporting wall of a hollow metal door or closure for receiving and frictionally retaining a strike, keeper or latch member (hereinafter referred to broadly by the terms strike or latch member), the latter being preferably mounted on the cabinet.

One of the objects of the present invention is to provide a novel catch assembly including a catch formed of a yieldable plastic composition having a hollow bore or longitudinal opening for receiving and frictionally gripping and retaining the projecting end of a strike, and a housing for said catch with the housing provided with means for detachably yet securely mounting and retaining the assembly in a supporting wall or member.

Another object of the present invention is to provide a novel catch assembly including a housing and a catch composed of a non-metallic, yieldable and resilient composition, the latter having substantial freedom of movement in the housing whereby the opening or bore of the catch may be readily and easily aligned with the rigid projecting end of the strike as it engages the enlarged open end of the catch prior to entry into its bore or opening. In view of this novel assembly in which the catch is free to shift in its housing, the projecting end of the strike will automatically enter the open, receiving end of the catch upon closing of the cabinet door or closure, for even though the opening in the catch may not be in accurate alignment with the projecting end of the strike or latch member, the catch will be moved laterally in its housing by the entering end of the strike into a position wherein the opening or bore of the catch will be aligned with the entering end of the strike.

The present invention further comprehends the provision of a novel catch assembly in which the housing for the catch member may be quickly and easily assembled in an opening in a support wall or surface of a hollow metal door and when forced into its intended location or operative position is automatically anchored in this wall. When so located, the housing is held by means of spring tongues or projections that engage the rear surface of the supporting wall and by an external anchoring flange that abuts the front of the supporting wall or surface and provides a stop to accurately locate or position the housing in the opening of the supporting wall.

In this novel embodiment, provision is made for removal or replacement of the catch assembly by providing openings in the supporting wall and aligned openings in the external anchoring flange, with each set of aligned openings being disposed in alignment with a spring tongue on the housing, whereby the insertion of a pointed, narrow tool through each set of aligned openings permits depressing of the aligned spring tongue and upon

2

operator grasping the external anchoring flange and pulling the assembly away from the opening in the supporting wall withdrawal of the assembly is effected.

The novel catch member is preferably formed of a plastic, resilient or flexible composition and by the term plastic it is intended to include polyethylene, neoprene or other compounded synthetic rubber, plastic or rubber-like material suitable for the purpose of receiving and frictionally gripping and retaining the projecting end of a rigid strike, keeper or latch member. Such material is capable of extended use and of being flexed or expanded as the rigid projecting end of the strike enters the opening of the catch member, whereupon it yieldingly grips this end and retains it and the door in closed position but permits the door to be readily opened when intended.

Further objects are to provide a construction of maximum simplicity, efficiency, economy and ease of assembly and operation, and such further objects, advantages and capabilities as will later more fully appear and are inherently possessed thereby.

In the drawing:

Figure 1 is a cross sectional view through the present novel catch assembly, the view being taken in a plane represented by the line 1—1 of Fig. 2 and viewed in the direction of the arrows.

Fig. 2 is a view in front elevation of the novel catch assembly.

Fig. 3 is a cross sectional view taken on the line 3—3 of Fig. 2 and viewed in the direction of the arrows.

Fig. 4 is a view in front elevation of a modified form of catch assembly.

Fig. 5 is a cross sectional view taken in a plane represented by the line 5—5 of Fig. 4 and viewed in the direction of the arrows.

Fig. 6 is a cross sectional view taken in a plane represented by the line 6—6 of Fig. 4 and viewed in the direction of the arrows.

Referring more particularly to the disclosure in the drawing and to the illustrative embodiment and detailed constructions therein shown, Figs. 1, 2 and 3 disclose one embodiment of the novel catch assembly which includes a housing 10 and a catch member 11 composed of a plastic composition, such as polyethylene, neoprene or other suitable flexible or yieldable and resilient plastic or compounded synthetic rubber or rubber-like material capable of use in the present assembly over an extended period of time and with a minimum of wear. This catch member is adapted to receive therein the projecting end 12 of a strike or latch member 13 which enters and is frictionally retained by the catch member each time the door or closure of a kitchen cabinet, wall cabinet or other storage cabinet is closed, and capable of releasing said projecting end 12 each time the door is opened.

55 The housing 10 is shown fixedly mounted in an opening in a wall or supporting surface 14 of a hollow metal door, and comprises a box-like member preferably formed of sheet metal and provided with oppositely disposed side walls 15 and 16, and 17 and 18. The opposite side walls 15 and 16 are of similar construction with each having its rear 19 bent or turned inwardly into substantially abutting relation and with the adjacent ends having a complementary opening 21.

The opposite side walls 17 and 18 are also of similar construction and have their outer or rear ends free and projecting beyond the rear inturned end 19 of the side walls 15 and 16. Each side wall 17 and 18 is formed or provided with an inwardly or forwardly extending spring tongue or resilient projection 23 bent outwardly from its side wall. An annular metal disc or washer 23a is affixed or secured to an inturned edge or flange 24 on the housing by having the metal defining the opening

25 in the disc or washer bent or seamed over the inturned edge or flange 24 of the housing at 26.

In the housing is loosely mounted the catch member 11 of resilient or flexible plastic composition. In the disclosed embodiment of Figs. 1, 2 and 3, the catch member comprises a substantially rectangular block composed of a plastic, resilient composition that is centrally cored to provide a longitudinally extending and outwardly or rearwardly tapered bore or opening 27 therethrough, the opening being flared substantially at its forward or inner end at 28 to facilitate entry and to guide or direct the projecting end 12 of the strike or keeper 13 into the opening 27.

The catch member 11 is somewhat smaller than the opening or space provided therefor in the housing 10, whereby the catch member is permitted lateral movement in all directions from its centered position to compensate for misalignment between opening in the catch member 11 and the strike or keeper 13. Such lateral freedom of movement permits the catch member in the housing to shift as the projecting end 12 of the strike or latch member 13 enters the opening 25 in the disc or washer 23^a and contacts the flared end 28 of the catch member 11 to move the latter into the position where the end 12 of the strike or latch member is centered in the bore or opening 27.

The catch member may be provided with an annular or continuous recess 29 at the rear thereof to add to its flexibility or yieldability as the projecting end 12 of the strike or latch member 13 moves to the limit of its entry into the bore or opening 27. When so inserted, the encompassing material of the catch member 11 is expanded or distorted and tightly grips and retains the strike or latch member 13 to maintain the door closed, but permits ready release of this strike or latch member when the door is intended to be opened. When the strike or latch member is released, the composition of the catch member being resilient or flexible, will return to its original conformation.

Figs. 4, 5 and 6 disclose an alternate embodiment of catch assembly in which the housing 31 does not enclose or encompass the catch member 32 in the manner shown in Figs. 1, 2 and 3, and this catch member 32 varies somewhat from that previously described. The housing has relatively short side walls 33 and 34 each having an inturned edge or flange 35 for receiving and retaining an edge of the catch member 32 in the housing. The opposite side walls are similar to the side walls 17 and 18 and similar reference characters have been applied thereto and to the annular metal disc or washer and its manner of mounting on the housing, all of which are similar to the embodiment shown in Figs. 1, 2 and 3.

The catch member 32 differs from the catch member 11 in that it comprises a rectangular sheet or relatively thin section of a plastic composition as described above with reference to the catch member 11. This plastic section being of substantially less thickness than the catch member 11, its bore or opening 36 is not intended to receive and encompass or contain the length of the projecting end 12 of the strike or latch member 13. The inner or front end of the bore or opening is flared at 37 for receiving and directing the projecting end 12 of the strike or latch member 13 into the bore and an outer or rearwardly projecting annular lip 38 is provided through which the entering or projecting end 12 of the strike or latch member 13 extends when the door is closed.

As in the embodiment of Figs. 1, 2 and 3, the catch member 32 is loosely positioned within its housing 31 and is permitted to move freely either laterally or longitudinally whereby it will be capable of aligning with and receiving the strike or latch member 13 even though the

latter may not be accurately centered with the opening 25 in the disc or washer 23^a. When the projecting end 12 of the strike or latch member 13 enters the opening 25, it will engage the enlarged or flared end 37 of the catch member 32 and move or shift the latter to the position in which the end 12 of the strike is free to enter the bore or opening 36 and pass therethrough to the position it occupies when the door is closed. When the door is in closed position, the strike is held firmly by the encompassing catch member 32, but the strike may be released and the door opened when desired.

To release and remove or replace the housing 10 with its catch member 11 and the housing 31 with its catch member 32, each disc or washer 23^a is provided with a pair of oppositely disposed openings 39 each in alignment with an opening 41 in the wall or supporting surface 14, and in further alignment with the outwardly projecting, free end of a spring tongue 23. By inserting a narrow screwdriver or other tool or object capable of projecting through the aligned openings 39 and 41 and depressing the free end of a spring tongue 23, the latter may be depressed sufficiently to withdraw the disc or washer 23^a and the housing 10 or 31 attached thereto. As the plastic catch 11, as well as the plastic catch 32, is carried in its housing, it will be removed with the housing.

Although reference is made to mounting either disclosed form of housing and catch member in a wall of a hollow door and the strike or latch member on the cabinet, it will be apparent that these parts may be reversed, if desirable.

Having thus disclosed the invention, we claim:

A catch assembly for the hollow metal door of a cabinet for receiving and retaining the projecting end of a latch member and retaining the door closed but permitting it to be opened when desired, said catch assembly including a housing mounted in an opening in a supporting wall of said door and providing an enclosure including spaced and oppositely disposed side walls, an inturned flange at the outer end of said side walls, a disc affixed to said inturned flange with said disc abutting the outer face of said supporting wall when the housing is mounted in said opening, and inturned flanges at the inner end of said housing, said housing and disc having an opening aligned with the opening in the supporting wall with said openings being of a size to loosely receive and through which the projecting end of the latch member extends when the door is closed, a catch member of a flexible and resilient plastic composition confined but loosely positioned within said housing to permit said catch member to bodily shift laterally in all directions, said catch member provided with a flared and rearwardly tapered bore therethrough for receiving said projecting end and the portion of said catch member defining said bore expanded by and frictionally gripping and retaining the projecting end of the latch member when the door is closed, said catch member being free to shift in its housing upon engagement of the projecting end of the latch member with the flared end of the bore and be moved by said projecting end to bring the bore of the catch member into alignment with said projecting end.
